UNITED STATES PATENT OFFICE.

JOHN A. WOLFE, OF TULSA, OKLAHOMA.

OIL TANK.

Application filed May 29, 1923. Serial No. 642,285.

To all whom it may concern:

Be it known that I, JOHN A. WOLFE, a citizen of the United States, residing at Tulsa, in the county of Tulsa and State of Oklahoma, have invented a new and useful Oil Tank, of which the following is a specification.

This invention relates to an oil tank which is especially adapted for receiving the oil directly from the oil well.

The general object of the invention is to provide certain novel features of construction by means of which the tank is kept sealed at all times, to prevent escape of the volatile contents contained in the crude oil, while readily permitting the inspection of the flow from time to time to ascertain whether the pump is working properly, and to determine the volume of flow therefrom.

The principles of the invention and the specific construction, by means of which they are embodied, will be more fully understood from the following detailed description taken in connection with the accompanying drawings which illustrate the preferred form of the invention.

In the drawings:

Figure 1 is a vertical sectional view through an oil tank, with the invention applied thereto.

Figure 2 is a plan view of the same with parts shown in section.

Figure 3 is a perspective view showing the relative arrangement of the inlet and outlet and other attachments.

The body 5 of the tank is constructed in the usual manner from sections of heavy gage metal, joined together in an air-tight manner over an interior frame-work, which is composed of angle irons 6 riveted together. A comparatively large casing 7 preferably about 16 inches in diameter, is located centrally of the tank and securely held at the top and bottom by angle irons 8 and 8^a, respectively. This casing protrudes a short distance above the roof 9 of the tank, where it is closed by a suitable removable cover 10 and extends to within three feet of the bottom. The connection with the roof is air-tight. An outlet pipe 11 extends through one side of the tank, and its intake end 11^a extends downwardly nearly to the bottom of the tank; while the normal oil level is indicated at 12. A vacuum line 13 also communicates with the interior of the tank through an opening 14 in the roof.

A pipe line 15, usually about two inches in diameter, extends directly from the pump to the tank. In accordance with the present invention this pipe line has two branches 16 and 17, one of which enters the upper end of the casing 7 at a point 18 just above the roof 9, while the other branch has a down-turned end 19 extending through an opening 20 in the roof 9, discharging directly into the tank but outside of the casing 7. The branches 16 and 17 are provided intermediate their ends with valve boxes 21 and 22 containing ball safety valves, either one of which may be held closed by the ball 23 while the other remains open.

The tank is also provided in its roof with a pressure relief valve 25, and a man-hole cover 26. It is to be understood that all connections are provided with the usual packing to provide air-tight joints, so that the oil is prevented from evaporating, and the volatile gases are prevented from escaping while the casing 7 and the outlet 11 is sealed by the liquid which is inside the tank.

Normally, while the pumps are in operation, the ball 23 remains over the valve in box 21. Whenever it is desired to ascertain if the pumps are working efficiently, or to determine the character of the oil discharged thereby all that is necessary is to remove the cover 10 and to shift the ball 23 to the position shown in dotted lines at 24, Figure 1, thus opening the valve in the box 21, while the valve in the box 22 is closed. After the inspection is completed, the ball 23 is replaced in its former position to permit the oil to be discharged directly into the tank. The cover 10 is then replaced on the upper end of the casing 7. It is to be noted, however, that during the removal of the cover 10, the volatile contents of the tank is prevented from escaping by reason of the liquid seal at the bottom of the casing.

Although the construction above described is particularly designed for use in connection with oil wells and pumps, the invention, of course, is not limited to such use, but may be used in connection with any pipe line through which liquid is discharged. It will also be understood that the specific construction herein described is merely illustrative, and that various modifications may be made therein within the scope of what is claimed without departing from the spirit of the invention or sacrificing any of its advantages.

What is claimed is:

1. In a device of the character described, the combination of a tank, a casing having its lower end within the tank and terminating near the bottom thereof and having an independently removable closure at its upper end, and a supply pipe having valve controlled branches leading into the body of the tank and the casing respectively.
2. In a device of the character described, the combination of a tank, a casing extending within the tank, an outlet pipe for the tank, the inner ends of said casing and pipe being normally sealed by the liquid within the tank, the upper end of said casing being outside of the tank and having an independently removable closure, and a supply pipe having branches leading into the body of the tank and the casing respectively, and individual valves for controlling said branches.
3. In a device of the character described, the combination of a tank, a casing extending through the roof of the tank and having its lower end spaced from the bottom thereof, an outlet pipe extending through the side wall of the tank above the lower end of the casing, a removable closure for the upper end of the casing, and a supply pipe having means for optionally discharging liquid either into the casing or into the body of the tank.
4. In a device of the character described, the combination of a tank, a centrally disposed vertical casing extending through the roof thereof and provided at its upper end with a removable closure, an outlet pipe extending through the side wall of the tank, the inner end of said pipe and the lower end of the casing being spaced from the bottom of the tank but below the normal level of the liquid within, and a supply pipe having valve controlled branches leading into the body of the tank and the casing respectively, said casing being materially larger in diameter than the supply pipe.
5. In a device of the character described,

the combination of a tank, a centrally disposed vertical casing extending through the roof thereof and provided at its upper end with a removable closure, braces inside the tank rigidly supporting said casing at its upper and lower ends, the lower end of the casing being below the normal level of the liquid inside the tank, and a supply pipe having one branch opening into the casing above the roof, having another branch extending through the roof into the interior of the tank but outside the casing, and separate valves for independently controlling the discharge of liquid through the respective branches.

6. In a device of the character described, the combination of a tank, a casing extending through the cover of the tank within the latter to a point above the bottom thereof, the lower end of the casing being open, means for opening or closing the upper end of the casing outside the tank, a supply pipe having valve controlled branches leading into the tank and casing respectively, and an outlet pipe for the tank having its inner end normally sealed by the liquid within the tank.

7. In a device of the character described, the combination of a tank, a centrally disposed vertical casing extending through the roof thereof and provided at its upper end with a removable closure, the lower end of the casing being below the normal level of the liquid inside the tank, and a supply pipe having one branch opening into the casing above the roof, having another branch extending through the roof into the interior of the tank but outside the casing, separate valve boxes in each branch containing valves, and a removable ball for the valves, whereby one of the valves may remain closed while the other is open, and vice versa.

In testimony that I claim the foregoing as my own, I have hereto affixed my signature.

JOHN A. WOLFE.
